SOUND TRANSLATING DEVICE

Herbert R. Warnke, Camden, N. J., assignor to
 Radio Corporation of America, a corporation of
 Delaware

Application April 28, 1934, Serial No. 722,821

4 Claims. (Cl. 179—115.5)

My invention relates to sound translating devices, and more particularly to loudspeakers of the movable coil or dynamic type having a permanent magnet field and a conical diaphragm.

5 In permanent magnet dynamic speaker design with which I am familiar, large permanent magnet field yokes usually comprising a multiplicity of bars have often been employed. The yokes and other parts of the speaker including the center and outer pole pieces are usually held together by bolts or rivets, and these structures have lacked desirable compactness and magnetic efficiency relative to bulk. Furthermore, as it is necessary that certain parts of the speaker be 10 critically positioned relative to each other, it has been necessary that the holes for the bolts or rivets which hold the speaker together be very accurately located. This, of course, is objectionable from a manufacturing standpoint as it adds 15 to the cost of and retards speed of production.

Also, welding has been used in assembling certain of the speaker parts. However, there are certain disadvantages in this method, namely, the structures must be subjected to heat which often causes warping and the misalignment of the parts, and forms must be employed to hold the various parts in position during the operations.

It is, accordingly, the primary object of my invention to provide a permanent magnet dynamic type loudspeaker and method of assembly therefor which will be free from the defects and disadvantages of the prior art as noted in the foregoing.

35 A further object of my invention is to provide a permanent magnet dynamic type loudspeaker of high magnetic efficiency relative to bulk and of a substantially small dimension from front to back and,

40 A still further object of my invention is to provide for a permanent magnet dynamic type loud speaker, a method of assembly for the several parts which is adaptable to speedy production yet which insures extreme accuracy in locating the parts relative to each other.

In accordance with my invention, I provide a dynamic type loudspeaker having permanent magnet field structure comprising one or more permanent U-shaped magnets.

45 In the structure including one magnet, the ends or poles of the magnet are held in contact respectively with the top end of a soft iron plate constituting an outer pole piece substantially the width of the magnet and the top end of a second soft iron plate which is disposed to the rear of

the first plate and is spaced therefrom by a non-magnetic spacing member. Fixed to the rear plate is a soft iron cylindrical center pole piece which extends forward and into a circular opening in the front plate to provide an air gap for the movable coil of a cone type diaphragm. To insure accurate location of the center pole piece in the opening in the front plate, I have devised a method of assembly whereby such accuracy is obtained although liberal tolerances may be allowed in the location of holes and studs therefor which hold the parts together.

In the embodiment of my invention which includes a plurality of U-shaped permanent magnets, the front and back plates are modified to provide contacting surfaces for the respective poles of the magnets.

50 Welded to the front plate is a forwardly extending housing or frame including a flange to which the rim of a cone diaphragm is attached. An opening substantially the width and thickness of a pole of the U-shaped magnet is provided in the housing through which the pole extends. The opening serves to prevent horizontal displacement of the magnet relative to the ends of the front and back plates and a single screw passes through the top of the magnet, extends downward and is threaded into the spacing member to prevent vertical displacement.

The novel features which I consider characteristic of my invention are set forth with particularity in the appended claims. The invention itself, however, both as to its organization and its method of operation, together with additional objects and advantages thereof, will best be understood from the following description of specific embodiments, when read in connection with the accompanying drawing, in which,

55 Figure 1 is a view in perspective of a permanent magnet dynamic type loudspeaker constructed in accordance with my invention and employing a single U-shaped permanent magnet.

Fig. 2 is a vertical sectional view of a loudspeaker wherein the structure shown in Figure 1 has been modified to employ a plurality of permanent U-shaped magnets.

Fig. 3 is a view partly in section and looking in the direction of the arrows on the line 3—3 of Fig. 2.

Fig. 4 is a rear view of the back plate employed in the structure shown in Fig. 2.

Fig. 5 is a view in section illustrating a method of assembly for certain parts of my improved loudspeaker.

Fig. 6 is a sectional view taken on the line 6—6 of Fig. 5.

Fig. 7 is a fragmentary sectional view further illustrating the method of assembly; and

5 Fig. 8 is an end view of a spacing member.

Referring, now, to the drawing wherein like numerals refer to like parts throughout, there is shown in Fig. 1 a dynamic type loudspeaker including permanent magnet field structure constructed in accordance with one embodiment of 10 my invention.

A frustro-conical diaphragm 1 is mounted within in a housing 3 and integral with the housing is a circular flange 5 to which the rim of the diaphragm is secured in any suitable manner. The housing 3, which is constructed of a light non-magnetic metal such as aluminum, is constituted by an open frame-work in order to further reduce weight and includes top and bottom portions 7 and 9, respectively, extending rearwardly of the flange. Back strips 11 and 12 are integral with the top and bottom portions 7 and 9, respectively, and serve as places of attachment for an assembly of the speaker parts which will 25 now be described.

The above noted assembly comprises a plate 13 which functions as an outer pole piece, a back plate 15, a center pole piece 17 fixed to the back plate 15, and a non-magnetic spacing member 19 interposed between the two plates. Mounted upon the assembly with its two poles held in contact respectively with the top ends of the front and back plates 13 and 15 is a permanent U-shaped magnet 21. The magnet 21 may 30 be made of cobalt steel to provide a maximum degree of magnetic efficiency. However, as cobalt steel is relatively expensive, in order to reduce manufacturing cost, I prefer to use chromium steel, which is comparatively inexpensive 35 and entirely satisfactory. The front plate 13, the back plate 15, and the center pole piece 17 are preferably constructed of soft iron to provide maximum magnetic permeability. As heretofore noted, the spacing member 19 is made of a non-magnetic material, such as a zinc alloy, for example. Thus, the magnetic flux is confined as 40 nearly as possible to the proper path which is, of course, between the outer and center pole pieces.

50 The front plate 13, which is substantially rectangular in shape and the width of the permanent U-shaped magnet 21, has its top end bent over to the front at right angles to provide a surface of sufficient area for overall contact with an end or pole of the U-shaped magnet 21. Formed in the front plate 13 is a circular opening 23 of sufficient size to allow the entrance of a voice coil 25.

60 Extending into and centered in the opening 23 in the front plate 13 is the center pole piece 17 which is of a smaller diameter than the opening. The space thus provided between the center pole piece 17 and the walls of the opening in the front plate 13 provides an air gap for the voice coil 25. It will be observed from the drawing that the center pole piece 17 is of a reduced diameter at the rear of the air gap and that the opening in the front plate 13 is countersunk. This acts to 65 confine the magnetic flux as nearly as possible across the air gap between the center and outer poles. A reduced cylindrical extension 27 terminates the center pole piece 17 at the rear and a hole is provided in the rear plate 15 into which 70 75 the reduced extension 27 fits with its end flat-

tened or riveted over to securely fix it to the plate.

The top of the back plate 15 is of substantially the same width and thickness as that of the pole of the U-shaped magnet 21 which is held in contact therewith. From the top downward, the plate 15 is of a gradually diminished width and is the shape of an inverted isosceles triangle, having its apex cut off even with the bottom edge of the center pole piece 17. The diminution in 10 the width of the back plate 15 is such that its side edges are tangent with the periphery of the rear face of the center pole piece 17. This reduces the amount of surface of the back plate which extends beyond the limits of the center 15 pole piece, thus reducing flux loss between the front and back plates.

Referring now to Fig. 2, it will be seen that I may include a plurality of permanent magnets in my improved loudspeaker, thus increasing its 20 magnetic efficiency. In this arrangement, it will be seen that the front plate 13a and back plate 15a extend downward and terminate in ends similar to their upper ends and so provide faces 25 against which the respective ends of a second U-shaped magnet 21a are held in contact.

In Fig. 4, it will be noted that the back plate 15a is of a reduced width at the center where the center pole piece 17 is secured and that it flares outwardly toward the top and bottom to 30 a width substantially that of the magnets.

From the above, it will be apparent that the plates 13 and 15 may be still further modified to accommodate more than two magnets. For example, extensions similar to those provided at 35 the bottoms of the plates in Fig. 2 may be provided at their sides. No illustration of this is thought to be necessary, as it is apparent that the structures at the sides of the plates would be a duplication of those at the tops and bottoms. 40

Interposed between the front plate 13 and the back plate 15 and spaced from and located above the center pole piece 17, in the structure shown in Fig. 1, is the non-magnetic spacing member 19 which serves to hold the plates including the 45 center pole piece in proper relationship. The ends of the spacing member 19 abut the inside faces of the plates respectively and are accurately positioned and positively held in place in a novel manner to be presently described.

positions and thus the center pole piece properly centered in the opening in the front plate.

The method of assembling the front plate 13, back plate 15, center pole 17 and the spacing member 19 will now be described with reference to Figs. 5, 6, 7 and 8 of the drawing.

As previously noted, the rear extension 27 of the center pole piece 17 is fitted into a hole in the back plate 15 and its end riveted over to firmly affix it thereto. This is the first step in the assembly of the above mentioned parts. Studs 31 on one end and studs 33 on the opposite end are integral with the spacing member. The studs are fitted into holes provided in the front 15 and back plates respectively and are riveted over, thus securing and locating the plates and center pole piece in their proper relationship to each other. It will, of course, be understood that the end of the center pole piece 17 must be very accurately located in the opening 23 in the front plate 13 to provide the air gap for the voice coil 25 which is located therein. It will be readily appreciated that if the studs 31 and 33 are positioned in their holes in the conventional manner, the holes, as well as the studs, must be very accurately located. This is not adaptable to high speed production and entails expensive operations.

To avoid the above noted disadvantages, I provide what I believe to be a novel method of assembly for the parts referred to, wherein liberal tolerances in drifting the holes and in locating the studs may be allowed.

The studs 31, located upon the end of the spacing member 19 which abuts the front plate 13, are of conventional design as will be noted from an inspection of Fig. 6. The location of the studs in the holes in the front plate 13 and the riveting over of their ends constitutes the second step in my method of assembly and is performed in the usual manner.

In accordance with my invention, the location of the center pole piece 17, relative to the back plate 15, and the spacing member 19 relative to the front plate 13, need not be achieved with any great degree of accuracy. However, the third step in my method of assembly, which is constituted by the affixation of the back plate 15 to the spacing member 19 and consequently the positioning of the center pole piece 17 in the opening in the front plate 13, must accurately locate the center pole piece as has been previously noted.

The third assembly step will now be described, reference being had to Fig. 8 of the drawing, which is a view of the end of the spacing member 19 which abuts the back plate 15. It will be seen that the studs 33 have base portions 35 which are hexagonal in shape and about the height of a conventional nut of the same dimensions, as will be more clearly seen in Fig. 6. At the base of the studs and extending under the corners of the hexagonal portions are circular grooves 37 in the spacing member 19.

The holes in the back plate 15 for the studs 33 are of a slightly larger diameter than the cylindrical portions of the studs but smaller than the hexagonal portions 35. Although I have found it convenient to make the base portions hexagonal, they may, of course, be made in other shapes.

In Fig. 5 is shown a form 39 with speaker parts which are to be assembled positioned thereon. The form 39 comprises a block 41 having integral therewith an upstanding cylindrical portion

43 and a cylindrical well 45 at the bottom thereof and extending within the block.

The cylinder 43 has an outer diameter that will permit the front plate 13 to be placed face downward upon the form with the cylinder fitting snugly within the opening 23 in the plate, as will be noted in Fig. 5. The inner diameter of the cylinder 43, as also will be noted, allows the center pole piece 17 to be fitted snugly therein. From the above, it will be seen that the thickness of the cylinder wall is substantially equal to the width of the air gap which is provided for the voice coil 25 in the assembled loudspeaker.

Considering the assembled front plate 13 and spacing member 19 as a unit and the assembled back plate 15 and center pole piece 17 as another unit, the assembly of these parts will now be described.

The front plate 13, with the spacing member 19 uppermost, is placed upon the form 39 with the cylindrical portion 43 of the form extending upwardly through the opening 23 in the front plate. Next the center pole piece 17 is fitted within the cylinder 43, the cylindrical ends of the studs 33 25 on the spacing member 19 are allowed to enter the holes provided for them in the back plate 15, and the pole piece 17 is extended into the well 45 provided in the form 39 therefor. As illustrated in Figs. 5 and 6, it will be seen that the center pole piece 17 will only be allowed to enter the cylinder 43 to a point where the back plate 15 will rest upon the hexagonal portions 35 of the studs 33 as the dimension of the hexagonal bases across their corners is greater than the diameter of the holes in the plate.

From an inspection of Figs. 6 and 7, it will be seen that application of sufficient pressure upon the back plate 15 will cause the edges of the holes in the plate to cut or shave off the corners of the 40 hexagonal basis 35 of the studs and thus form for themselves new tightly fitting studs constituted by the mutilated hexagonal bases. A conventional press or the like (not shown) is utilized to exert pressure upon the back plate until its under 45 face is flush with the adjacent end of the spacing member, and in so doing, the holes in the plate are caused to act upon the hexagonal bases of the studs in the manner described above. It is, of course, obvious that the material from which the 50 studs and spacing member are constructed is softer than the back plate.

In order to prevent the shaved off fragments of the hexagonal bases 35 of the studs 33 from becoming wedged between the plate 15 and the 55 spacing member 19, and so preventing them from being completely pressed together, the circular wells 37 in the spacing member at the base of the studs are provided to receive the shavings.

In Fig. 6, it will be noted that the studs 33 are not in exact alignment with the holes in the back plate 15. However, from the foregoing, it will be seen that, in spite of the misalignment of the parts, the center pole piece 17 is accurately located within the opening 23 in the front plate 13 65 to provide an air gap for the voice coil 25.

At the completion of the above described operation, the ends of the studs 33 are flattened or riveted over, and removal of the assembly from the form 39 completes the operation.

In connection with the structure shown in Fig. 2, wherein two U-shaped magnets are employed, it will be noted that a second spacing member 19a is utilized to further strengthen the union between the back and front plates 13a and 15a, re- 75

spectively. The second spacing member 19a is located relatively in the same relationship below the center pole piece 17 as the first spacing member 19 is located above, is substantially of the same construction, and is secured to the front plate 13a and back plate 15a in the same manner. The same method of assembly as described in connection with the structure shown in Fig. 1 is followed throughout, and it will be obvious that the assembly form 39 need only be slightly modified to accommodate the bent over bottom end of the front plate 13a.

Upon the completion of the assembly operations described above, the surfaces of the back plate 15 and front plate 13 upon which the ends of the U-shaped magnet 21 are to be located are ground to insure uniform contact therewith. The assembly is then attached to the diaphragm cone housing 3 by welding the front plate 13 to the back strips 11 and 12 thereof, as will be seen in Fig. 1.

Provided in the top of the cone housing 3 is the opening 47 which serves to locate the U-shaped magnet 21 in proper relation to the front 25 and rear plates 13 and 15, as is clearly shown in Fig. 3. The magnet 21 is placed in position upon the front and back plates with a pole extending through the opening 47 and a screw 49, passed through a hole in its top, extends downward and 30 is threaded into the spacing member 19. It will be observed that the opening in the cone housing prevents horizontal displacement of the magnet and the screw prevents vertical dislodgement.

It will be noted in Fig. 1 that I have utilized 35 the bottom portion 9 of the cone housing for mounting an audio transformer or the like. However, in the construction shown in Fig. 2 the bottom 9a of the housing 3a is constructed substantially like the top portion 7a thereof and the 40 second U-shaped magnet 21a is located and retained in position by the opening 47a and the screw 49a threaded into the second spacing member 19a.

From the foregoing, it will be seen that I have 45 provided a permanent magnet dynamic type loudspeaker of exceptionally compact design. Furthermore, the permanent magnet structure has been positioned relative to the diaphragm so as to make the unit as shallow as possible 50 without the sacrifice of magnetic efficiency. Such characteristics in a loudspeaker make it particularly adaptable to use in an automobile radio, for example.

Although I have used both riveting and welding in assembling my loudspeaker, it will be noted 55 that the riveting operations are adaptable to high speed production without the sacrifice of accuracy and are free from the disadvantages of the prior art. Furthermore, the points of the structure which are subjected to welding are located 60 where any warping caused by heat cannot affect the parts which must be accurately positioned.

Although I have shown and described specific embodiments of my invention, I am fully aware that many modifications thereof are possible. My invention, therefore, is not to be restricted except insofar as is necessitated by the prior art and by the spirit of the appended claims.

I claim as my invention:

1. In a loudspeaker including permanent magnet field structure and a voice coil, the combination of a plate comprising an outer pole piece 10 and having an opening therein, a second plate of magnetic material spaced from said first named plate, a center pole piece attached to said second named plate and extending into said opening in said first named plate whereby an air 15 gap for said voice coil is provided, and non-magnetic means spacing said plates from each other and maintaining said plates in such relation as to provide said air gap.

2. In a dynamic type loud speaker, the combination of a plate comprising an outer pole piece, a second plate spaced from said first named plate, non-magnetic means maintaining said plates in spaced relation, a center pole piece attached to said second named plate, and a permanent magnet having its poles respectively in contact with portions of said first and second named plates, said magnet being so disposed with respect to one of said plates as to have at least a portion thereof in the plane of said latter plate. 30

3. In a loudspeaker including a diaphragm and a voice coil, the combination of a housing for said diaphragm having a plurality of openings therein, a plate comprising an outer pole piece having an opening therein and attached to the back of said housing, said plate having an end thereof bent over and extending into said housing through one of said openings therein, a second plate disposed to the rear of said first named plate, a non-magnetic spacing member interposed between and having its ends respectively attached to the inner faces of said first and second named plates, a center pole piece attached to said second named plate and extending forward into said opening in said first named plate 45 whereby an air gap is formed for said voice coil, and permanent magnet structure having a pole thereof extending through one of said openings in said housing and contacting with the bent over portion of said first named plate and having its other pole contacting with an end of said second named plate. 50

4. The invention as set forth in claim 3 characterized in that said magnet structure comprises a plurality of permanent magnets each having a pole thereof extending through one of said openings in said housing and contacting with an end portion of said first named plate and having the other pole thereof contacting with one end of said second named plate. 60

HERBERT R. WARNE.
